UNITED STATES PATENT OFFICE

2,056,071

REEL FOR METAL STRIP

Edwin E. Moore, Chicago, Ill., assignor to American Sheet and Tin Plate Company, a corporation of New Jersey

Application March 26, 1935, Serial No. 13,167

1 Claim. (Cl. 242—68)

This invention relates to reels or coil centers of the type now commonly used to carry coils of metal strip which is to be cold rolled by means of a 4-high mill, one of the objects being to provide 5 a reel of this character which may be easily handled and mounted. Another object is to provide an improved means for securing the ends of metal strip to such reels. Other objects may be inferred.

10 An example of a reel embodying the features of the invention is illustrated by the accompanying drawing, Figure 1 being a side elevation showing the improved securing means, with the bearings for the reel shown in section, and Figure 2 being 15 a cross-section from the line II—II in Figure 1.

More specifically, this reel includes a solid cylindrical body 1 on which strip may be coiled and which may be keyed to an axle 2 by keys 10, the two parts being as constructed to form a solid 20 unit which will not collapse even though the strip be coiled very tightly. The axle 2 projects beyond the ends of the body 1 so as to provide journals 2^a and fluted ends 2^b and end portions 1^a are connected to the axle 2 and body 1 in any 25 suitable manner (not shown).

Roller bearings 3 are permanently mounted on the journals 2^a close to the ends of the body 1. The housings of these bearings have cylindrical casings 3^a and integral spaced annular flanges 3^b, and function to mount the reel in suitable 30 brackets or to permit the reel to be rolled along tracks in the manner illustrated. These casings 3^a are held against lateral shifting by retaining collars 8 thus holding the same snugly against the 35 tapered portions 1^a.

Also, the bearing housings provide extensions 3^c through which screws 4 may be passed so as to engage threaded holes formed in end portions 1^a of the body 1 if so desired. When the reel is 40 being rolled along tracks these screws may be used to prevent relative rotation of the bearing housings and the journals, whereby skewing of the reel is prevented. These screws are removed when the bearings are mounted in a coil box 45 (not shown), this being for the purpose of permitting the strip to coil or uncoil from the rotating body 1 while the casings 3^a are held stationary. Most 4-high mills include tensioning or driving devices, and the fluted ends 2^b may be 50 used to couple such devices to the reel.

A longitudinal groove 5 is formed in the sur-

face of the body 1, in which a jaw 6 is fitted. This jaw has a number of cam surfaces 6^a on one of its sides which are engaged by cam surfaces 7^a on the side of a laterally shiftable jaw 7 which is also fitted into the groove. When this bar is longitudinally moved the jaw will be moved circumferentially of the body so as to effectively clamp the end of a strip between itself and the side of the groove.

The groove 5 may be slightly inwardly flared 10 and the sides of the elements 6 and 7 which contact the sides of this slot may be beveled, all as is shown by Figure 2, whereby the parts may be retained in the groove by circular rings 9 which encircle the extreme ends of the body 1 and serve 15 to hold the jaw 6 and movable bar 7 against peripheral displacement.

When it is desired to clamp the end of a strip 20 to the reel, the end of the strip is inserted between the adjacent faces of the groove 5 and jaw 6, the bar 7 being moved to the right so as to permit this. Thereafter the bar is forced to the left, this causing the jaw to tightly clamp the end of the strip against the side of the groove.

Preferably, the bar should project beyond the 25 right-hand end of the body 1 a sufficient distance to permit the use of a hammer in effecting its forcing to the left, and it should project to the left sufficiently far when forced to its full clamping position to permit the use of a hammer in 30 forcing it to the right to release the end of the strip.

I claim:

A reel for carrying coils of metal strip, said reel including a cylindrical body on which said strip may be coiled, axles fixedly projecting from the ends of said body and providing journal portions, antifriction bearings permanently mounted on said journal portions, said bearings having cylindrical externally flanged casings adapted for 35 mounting on suitable brackets or to roll along spaced tracks and which are normally free to rotate relative to said journal portions and said cylindrical body, and releasable means for preventing rotation of said casings relative to said journal portions and said cylindrical body, whereby 40 said casings may be locked to cause the same, said journal portions and said cylindrical body to 45 turn as a unit which may travel over said tracks without material skewing.

EDWIN E. MOORE.
